KNOB FOR AN ENDODONTIC INSTRUMENT

William Henry Boggs, 18887 Valley View Drive, River-view, Mich. 48192, and George Reed Govers, 118 Granite St., Medfield, Mass. 02052

Filed Dec. 21, 1970, Ser. No. 26,734

Term of patent 14 years

Int. Cl. D24—03

U.S. Cl. D24—1

FIG. 1

FIG. 2

FIG. 3

FIG. 4

FIG. 5

FIG. 6

FIG. 1 is an enlarged scale side elevation of a knob for an endodontic instrument showing our new design;

FIG. 2 is a plan view of one end thereof;

FIG. 3 is a plan view of the opposite end thereof;

FIG. 4 is a cross-section taken on line 4—4 of FIG. 1;

FIG. 5 is a perspective view of an endodontic instrument taken at a reduced scale; and

FIG. 6 is a side elevation thereof.

We claim:

The ornamental design for a knob for an endodontic instrument, as shown and described.
